UNITED STATES PATENT OFFICE.

JOHN C. CORCORAN, OF ST. PAUL, MINNESOTA.

DESIGN FOR A BOTTLE-STOPPER.

SPECIFICATION forming part of Design No. 33,101, dated August 21, 1900.

Application filed May 21, 1900. Serial No. 17,493. Term of patent 7 years.

To all whom it may concern:

Be it known that I, JOHN C. CORCORAN, a citizen of the United States, residing at St. Paul, in the county of Ramsey and State of Minnesota, have invented and produced a new and original Design for Bottle-Stoppers, of which the following is a specification, reference being had to the accompanying drawings, forming a part thereof.

10 This invention consists in the unitary design shown in the accompanying illustration, in which—

Figure 1 is a side elevation. Fig. 2 is a top plan view, and Fig. 3 is a bottom plan view.

15 Referring to the drawings by letter, A represents the lower portion of the stopper tapering from its lower toward its upper end and merging into a circular projection having its lower surface B curving outwardly and 20 upwardly and its upper surface D curving

outwardly and downwardly and with a deeply-sunken recess in the rim of the projection. The upper part D merges into a central cylindrical column F, having a flat upper surface. The points of juncture between the 25 parts A and B and the parts D and F are formed with sharp angles or at substantially right angles. An aperture a extends centrally through the whole stopper.

Having thus described my invention, what 30 I claim as new is—

The design for a bottle-stopper, as herein shown and described.

In testimony whereof I affix my signature in presence of two witnesses.

JOHN C. CORCORAN.

Witnesses:

L. FEESER, Jr.,

GEO. E. SCALES.
